ABSTRACT OF THE DISCLOSURE

A stud assembly for shoes, for example, golf shoes comprises a flange member for engagement in a conventional socket in the sole of a shoe, the flange spreading the load over a suitable area of the sole of the shoe and a stud member removably press fitted into a central bore in the flange member.

This invention is concerned with studs for footwear, particularly sporting footwear such as golfing shoes, cricket boots, soccer and rugby boots and the like. As the invention is primarily concerned with studs for golfing shoes, such sporting footwear will be hereinafter referred to simply as shoes.

A common form of golfing stud comprises a threaded socket embedded in the sole of the golfing shoe and a stud member having a threaded pin engaging the socket, a broad flange for engaging the sole of the shoe and the stud itself extending from the flange. Therefore, as the stud member becomes worn it should be possible to unscrew it from the socket and substitute a new stud member. In practice, however, problems arise through damage to the threads of the socket or of the stud member and the assembly is also subject to corrosion through the action of the surface dressing employed on golfing greens.

It is an object of the present invention to obviate or mitigate these difficulties.

The present invention is a flange member for shoes, including a flange for engaging the sole of a shoe, a boss projecting from the upper surface of the flange and adapted to fit a socket in the sole of the shoe, a slot extending across the boss, and a bore passing through the flange and boss and tapering from at least one end to a minimum cross-section.

The present invention is also the combination of a flange member, as defined in the last preceding paragraph, and a stud member which includes a stud, a flange engaging the lower surface of the flange of the flange member, and a pin projecting from the flange and engaging the bore of the flange member, the pin being retained in the flange member by a portion of increased cross section on that side of the bore minimum cross section which is remote from the flanges.

The present invention is further the combination as defined in the last preceding paragraph located in a socket, the pin expanding the wall of the boss into engagement with the socket.

The present invention is additionally a shoe having embedded in the sole thereof sockets each of which has located therein the combination defined in the second last preceding paragraph.

An embodiment of the present invention will now be described, by way of example, with reference to the accompanying drawing, in which:

FIG. 1 is a sectional view of one part of a stud assembly according to the present invention; and

FIG. 2 is an elevation of another part of a stud assembly according to the present invention.

2

The two parts of the assembly illustrated in the drawing are intended to be used in combination with each other and a conventional threaded socket which is embedded in the sole of a golfing shoe.

5 In FIG. 1 a flange member 10 is illustrated having a broad flange 11 for engaging the sole of a golfing shoe. A recess 12 is provided in one surface, the lower surface 13 of the flange 11, and from the other surface 14 projects a boss 15. The external surface of the boss 15 is threaded and dimensioned to match the threaded socket in the shoe sole. A bore 18 passes through the boss 15, the bore 18 tapering from both ends to a minimum cross section at 19. A slot 20 is provided through the boss 15.

A stud member 25 is shown in FIG. 2 and comprises a 15 stud 26, a flange 27 and a pin 28. The flange 27 and pin 28 are dimensioned to engage the recess 12 and bore 18 respectively of the flange member 10, and at its upper end the pin 28 is provided with a portion 30 of increased cross section. Adjacent the flange 27, the stud 26 is provided with a ridge 31 which allows the stud to be gripped by a tool for removal.

The complete stud assembly includes a socket which is embedded in the sole of the shoe. To fit the assembly, the boss 15 of the flange member 10 is located in the 25 socket and pushed home so that the surface 15 of the flange 11 is located against the sole of the shoe. It is not necessary to screw the member 10 into position since the flange member is of a material such that the threads of the boss 15 are resilient and thus will adapt to the thread 30 configuration of the socket in any relative angular position, and will yield to permit movement of the boss 15 into the socket past the threads of the socket. The stud member 25 is then taken and the pin 28 passed through the bore 18. The portion 30 forces apart the two halves 35 of the boss one on either side of the slot, as it passes the minimum cross section 19 and is thereby retained against accidental withdrawal. The diameter of the pin is sufficient to maintain the halves of the boss in expanded position so that the threads on the boss and socket engage and the assembly is locked together in position on the shoe, the flange 27 being seated in the recess 12. The stud member 40 may be withdrawn by an axial pull, the ridge 31 being gripped by pincers, but such an axial pull is much greater than any likely to be encountered in normal use of the 45 shoes.

It is desirable to make the flange member of a plastics material, such as nylon, and the stud member of a corrosion resistant material such as cadmium or zinc-plated or 50 similarly treated steel or other metal.

It is a feature of this stud that it will not damage in any way the socket in the sole of the shoe and an added advantage is that sockets which would not take a conventional stud because of damage or corrosion previously mentioned will be able to be restudded by the invention.

Additionally if shoe manufacturers were to put these studs in during manufacture, the socket, even after several restuddings, would still be undamaged and able to take a conventional threaded stud if desired. Also shoe manufacturers should find it considerably easier to assemble the studs of this invention, than to assemble conventional studs and therefore show production economies.

Modifications may be made to the embodiment described. For example, it is not necessary that the external surface of the boss be threaded. Parallel grooves would serve and indeed a smooth surface could prove adequate, the thread in the socket cutting its own grooves as the boss is expanded.

70 If the stud is to be subjected to particularly rough treatment, it is desirable to provide the bore in the flange member above the minimum cross section 19 with a uni-

form diameter defining an upwardly facing shoulder above the minimum cross section 19. In this case the pin 28 would be correspondingly stepped. This modification provides a more secure anchorage for stud member.

We claim:

1. A flange member for shoes, including a flange for engaging the sole of a shoe, a boss projecting from the upper surface of the flange and adapted to fit a socket in the sole of the shoe, a slot extending across the boss, and a bore passing through the flange and boss and tapering from at least one end to a minimum cross section.

2. A member as claimed in claim 1, in which said bore tapers from both ends to said minimum cross section.

3. A member as claimed in claim 1, in which the external surface of the boss is threaded.

4. A member as claimed in claim 1, including a recess around said bore on the lower surface of the flange.

5. A flange member for shoes as claimed in claim 1, in combination with a stud member comprising a stud, a flange engaging the lower surface of the flange of the flange member, and a pin projecting from the flange and engaging the bore of the flange member, the pin being re-

tailed in the flange member by a portion of increased cross section on that side of the bore minimum cross section which is remote from the flanges.

6. A combination as claimed in claim 5, located in a socket, the pin expanding the wall of the boss into engagement with the socket.

7. A shoe having embedded in the sole thereof sockets each of which has located therein the combination claimed in claim 5.

8. A member as claimed in claim 5, in which said bore tapers from both ends to said minimum cross section.

9. A member as claimed in claim 5, in which the external surface of the boss is threaded.

10. A member as claimed in claim 5, including a recess around said bore on the lower surface of the flange.
